(57) **CLAIM**

The ornamental design for a combined cross and ribbon, as shown and described.

DESCRIPTION

FIG. 1 is a perspective view of the top, side, and front of a combined cross and ribbon in accordance with my design;
FIG. 2 is a left side elevational view thereof;
FIG. 3 is a front elevational view thereof;
FIG. 4 is a right side elevational view thereof;
FIG. 5 is a rear elevational view thereof;
FIG. 6 is a top plan view thereof;
FIG. 7 is a bottom plan view thereof;
FIG. 8 is a perspective view of the top, side, and front of a slightly modified embodiment thereof;
FIG. 9 is a left side elevational view thereof;
FIG. 10 is a front elevational view thereof;
FIG. 11 is a right side elevational view thereof;
FIG. 12 is a rear elevational view thereof;
FIG. 13 is a top plan view thereof; and,
